(57) **ABSTRACT**

A cycling shoe has a sole and an upper attached to the sole. An adjustable closure panel extends across an opening in the upper. A lever assembly is exposed at an outer, rear surface of the upper, and is movable about a hinge between a first position and a second position. One or more passages extend through the cycling shoe to accommodate one or more cables to connect the lever assembly to the adjustable closure panel. The lever assembly is configured such that moving the lever assembly between the first position and the second position causes the one or more cables, if connected between the lever assembly to the adjustable closure panel, to tighten or loosen the closure panel relative to the upper.

CYCLING SHOE CLOSURE MECHANISM

CROSS-REFERENCE TO RELATED APPLICATIONS

This application is the National Stage of International Application No. PCT/US19/34496, filed May 30, 2019, which claims the benefit of U.S. Provisional Patent Application No. 62/678,526, filed May 31, 2018. The contents of these prior applications are incorporated by reference herein in their entirety.

FIELD OF THE INVENTION

This disclosure relates to a cycling shoe and, more particularly, relates to a closure mechanism for a cycling shoe.

BACKGROUND

A multisport competition, such as triathlon (or duathlon), is one in which an athlete races in a continuous series of stages in different racing disciplines, such as swimming, cycling, running, and transitions between the different disciplines. It is important for such athletes to not only perform at a high level in each discipline of a particular race, but also to transition between disciplines as quickly as possible.

SUMMARY OF THE INVENTION

A cycling shoe is disclosed herein that, in a typical implementation, is not only highly aerodynamic, but also one that is easy to put on and take off quickly, which can facilitate very quick transitions in multisport competition, for example.

In one aspect, a cycling shoe has a sole and an upper attached to the sole. An adjustable closure panel extends across an opening in the upper. A lever assembly is exposed at an outer, rear surface of the upper, and is movable about a hinge between a first position and a second position. One or more passages extend through the cycling shoe to accommodate one or more cables to connect the lever assembly to the adjustable closure panel. The lever assembly is configured such that moving the lever assembly between the first position and the second position causes the one or more cables, if connected between the lever assembly to the adjustable closure panel, to tighten or loosen the closure panel relative to the upper.

In a typical implementation, loosening the one or more cables that connect the lever to the adjustable closure panel facilitates lifting the closure panel away from the upper so that a foot can be inserted or removed from the cycling shoe with ease.

In some implementations, the lever assembly is configured such that: in the first position, the lever assembly substantially conforms to a contour of the rear surface of the upper, and in the second position, the lever assembly extends away from the upper in a rearward direction from the rear surface of the upper.

According to certain implementations, each of the one or more cables extends through a projection portion of the sole of the cycling shoe, or some other portion of the sole of the cycling shoe between the lever assembly and the adjustable closure panel. Moreover, each of the one or more cables may extend from the lever assembly, into a rear hole in a rear portion of the sole, through the sole, to a forward hole in a side surface of the sole, and to the closure panel.

In a typical implementation, there are one or more cable connectors attached to the closure panel, where each cable connector facilitates connecting the one or more cables to the closure panel.

5 In some implementations, the lever assembly has a cable carriage for coupling the one or more cables to the lever assembly. The cable carriage may define one or more openings, or anchors, through which the one or more cables can pass or to which the one or more cables can be attached 10 when coupled to the lever assembly. In some such implementations, the cable carriage may include a guide (e.g., a track or recess) that extends along the lever assembly between a proximal part of the lever assembly and a distal part of the lever assembly. The cable carriage may be coupled to and movable along the guide (e.g., track or recess) between a portion of the guide closer to the proximal part of the lever assembly and a portion of the guide closer to the distal part of the lever assembly.

15 20 According to certain implementations, the lever assembly further includes a tension adjuster for adjusting a position of the cable carriage along the guide (e.g., track or recess). In some implementations, the tension adjuster includes a knob and a threaded rod, which may be supported by a bracket portion of the lever assembly, for example, in a manner that permits the tension adjuster to be rotated about an axis but prevents the adjuster from being moved in an axial direction along the axis.

25 In some implementations, the cable carriage has surfaces 30 that define a threaded hole through the cable carriage, and the threaded rod of the tension adjuster passes through, and engages, the threaded hole of the cable carriage.

One or more cables may connect the lever assembly to the adjustable closure panel.

35 40 The one or more cables may include one, and only one, cable. In some implementations, the one, and only one, cable extends from a first cable connector at a first lateral edge of the closure panel, through a first one of the passages, through a first cable hole in the cable carriage, through a second cable hole in the cable carriage, through a second one of the 45 passages, and to a second cable connector at a second lateral edge of the closure panel, opposite the first lateral edge of the closure panel.

45 50 The one or more cables may include a first cable and a second cable. In some implementations, the first cable extends from a first cable connector at a first lateral edge of the closure panel, through a first one of the passages, and to the cable carriage, and the second cable extends from a second cable connector at a second lateral edge of the closure panel opposite the first lateral edge of the closure panel, through a second one of the passages, and to the cable carriage.

55 In some implementations, the hinge has a first portion that connects a first part of the lever assembly to a first lateral portion of the upper (e.g., via an extension coupled to the upper); and a second portion that connects a second part of the lever assembly to a second lateral portion of the upper (e.g., via the extension). The first portion of the hinge is separated from the second portion of the hinge by a space, and the cycling shoe is configured such that the one or more cables pass through the space when lever assembly moves between the first position and the second position.

60 65 Certain implementations include a strip of material attached to a side surface of the cycling shoe and that extends to the opening in the upper. The strip of material has sufficient stiffness and is placed in such a way that it will hold the opening in the upper in a more open position and

in contact with the closure panel, making an opening in the cycling shoe for a foot larger than it otherwise might be.

In another aspect, a cycling shoe includes a sole and an upper attached to the sole. An adjustable closure panel extends across an opening in the upper. A lever assembly is exposed at an outer, rear surface of the upper. The lever assembly is movable about a hinge between a first position and a second position. One or more passages extend through a sole (or projection portion of the sole) of the cycling shoe. One or more cables extend through the one or more passages and connect the lever assembly to the adjustable closure panel. In some implementations, a strip of material is attached to a side surface of the cycling shoe and extends to the opening of the upper. The lever assembly is configured such that moving the lever assembly between the first position and the second position causes the one or more cables to tighten or loosen the closure panel relative to the upper.

In yet another aspect, a cycling shoe has a sole and an upper coupled to the sole. A projection portion extends off a bottom surface of the sole behind a cleat (attachment) portion of the sole. The projection portion has a first lateral side surface, a second lateral side surface at an opposite side of the cycling shoe from the first lateral side surface, a bottom surface, and rounded lateral edges that connect each of the first and second lateral side surfaces to the bottom surface.

In a typical implementation, each of the rounded lateral edges has a radius of at least 7 mm.

The cycling shoe typically has a means for attaching a cycling cleat to sole in the cleat portion of the sole, and, in some implementations, a cycling cleat attached to the cleat portion of the sole. In some such implementations, the projection portion has a front side surface that faces the cycling cleat, and there is a space between the front surface of the projection portion and the cycling cleat.

In some implementations, the projection portion has one or more passages through it to accommodate one or more cables for connecting a lever assembly to an adjustable closure panel on the shoe. The lever assembly can be configured, as described elsewhere herein, such that moving the lever assembly between the first position and the second position causes the one or more cables, if connected between the lever assembly to the adjustable closure panel, to tighten or loosen the closure panel relative to the upper.

In a typical implementation, each lateral side surface of the projection portion extends from a bottom surface of the sole flush with or very close to flush with a corresponding lateral side surface of the sole. Moreover, in a typical implementation, each lateral side surface of the sole is flush with or very close to flush with a corresponding lateral side surface of the upper.

The projection portion, in some implementations, has a rear surface that slopes upward from the bottom surface of the projection portion to a rear of the sole or upper. Moreover, the rear surface of the projection portion typically is flush with or very close to flush with a corresponding rear surface of the sole and/or upper.

In some implementations, the projection portion is configured such that a furthest point of a trailing edge of the shoe, which is part of the projection portion, in a 55-degree toe-down position is between 14 millimeters and 47 millimeters from the sole, or from where the sole would be if the projection portion were not present. In some implementations, the furthest point of the trailing edge of the shoe in a 55-degree toe-down position is between 17 millimeters and

37 millimeters from the sole, or from where the sole would be if the projection portion were not present.

In some implementations, one or more of the following advantages are present.

5 A cycling shoe is disclosed that is both highly aerodynamic (particularly in a toe-down configuration) and easy to put on and take off quickly. This makes the cycling shoe particularly well suited for use in multisport events, such as triathlon or duathlon, where both aerodynamics while riding and quick transition times between race segments (e.g., from swimming to cycling, from cycling to running, from running to cycling, etc.) are highly desirable. The shoe is extremely easy to loosen and tighten—switching from an open (or loose) configuration (where the shoe can be put on or taken off easily) to a closed (or tight) configuration (where the shoe is tightly secured onto a cyclist's foot), with one simple movement—like the flip of a switch.

10 Other features and advantages will be apparent from the 20 description and drawings, and from the claims.

BRIEF DESCRIPTION OF THE DRAWINGS

FIG. 1 is a right side view of an exemplary implementation 25 of a cycling shoe.

FIG. 2 is a left side view of the cycling shoe of FIG. 1.

FIG. 3 is a rear view of the cycling shoe of FIG. 1.

FIG. 4 is a right side view of the cycling shoe in FIG. 1, 15 with the lever assembly in an open configuration.

30 FIG. 5 is a right side view of an alternative implementation of a cycling shoe.

FIG. 6 is a left side view of the cycling shoe of FIG. 5.

FIG. 7 is a forward facing view, from the rear, of the 35 cycling shoe of FIG. 5.

FIG. 8 is a right side view of another alternative implementation of a cycling shoe.

FIG. 9 is a left side view of yet another implementation 40 of a cycling shoe coupled to a cleat.

FIG. 10 is a cross-section of FIG. 9 (taken at line A-A).

45 FIGS. 11 and 12 show a schematic representation of an exemplary shoe that includes a projection portion, on the foot of a cyclist who is riding in direction M in a toe-down configuration, with apparent wind indicated.

FIGS. 13 and 14 show a similar schematic representation 50 of a shoe that does not include a projection portion.

FIG. 15 shows a computational fluid dynamics simulation of a shoe that includes a projection portion.

FIG. 16 shows a computational fluid dynamics simulation 55 of a shoe that does not include a projection portion.

FIG. 17 shows computational fluid dynamics simulation of a shoe that includes a projection portion.

FIG. 18 shows a computational fluid dynamics simulation of a shoe that does not include a projection portion.

55 FIG. 19 shows computational fluid dynamics simulation of a shoe that includes a projection portion.

FIG. 20 shows a computational fluid dynamics simulation of a shoe that does not include a projection portion.

Like reference characters refer to like elements.

DETAILED DESCRIPTION

FIGS. 1-4 show an exemplary implementation of a cycling shoe 100 that is highly aerodynamic and easy to put on and take off quickly. This makes the cycling shoe 100 particularly well suited for use in multisport events, such as triathlon or duathlon, where both aerodynamics while riding and quick transition times between race segments (e.g., from

swimming to cycling, from cycling to running, from running to cycling, etc.) are highly desirable.

In various implementations, the cycling shoe 100 may include one or more of a variety of features that contribute to its aerodynamic nature. For example, in the illustrated implementation, the overall shape of the cycling shoe 100, including a projection portion 102 on the bottom of the cycling shoe 100, contributes to the shoe's overall aerodynamic nature. As another example, in the illustrated implementation, the location of the lever assembly 104 (the manipulation of which activates the shoe's closure mechanism) at the rear of the cycling shoe 100 behind the heel contributes to the shoe's overall aerodynamic nature. Either of these features alone can have a positive impact on the shoe's overall aerodynamic nature. In implementations that include both of these features, the positive impact on the shoe's aerodynamic nature is even greater.

In various implementations, the cycling shoe 100 may include one or more of a variety of features that help make the shoe easy to put on and take off quickly. For example, in the illustrated implementation, the shoe has a closure mechanism that is very easy to use. Indeed, the shoe closure mechanism in the illustrated implementation can be closed or opened with one simple movement (e.g., by moving the lever assembly 104 at the rear part of the cycling shoe between its position shown in FIGS. 1-3 (shoe closed) and its position shown in FIG. 4 (shoe open)—like the flip of a switch). As another example, in the illustrated implementation, the cycling shoe 100 may be fitted with one or more strips of semi-rigid, but flexible material (not shown in FIGS. 1A and 1B, but see 550 in FIGS. 5-7) configured to urge the upper 110 open (as in FIG. 4), the closure panel 106 is pushed away from the upper 110, making the opening 112 for the foot large. This enables the cyclist to easily slip his or her foot inside the shoe when the shoe is open. Either of these features alone can have a positive impact on the shoe's ease of use. In implementations that include both of these features, the positive impact on the shoe's ease of use is even greater.

These various features are described in detail herein. In various implementations, a cycling shoe may be provided that includes one or more (any combination of), or all, of these features.

Focusing again on FIGS. 1-4, the illustrated cycling shoe 100 has a sole 108 and an upper 110 attached to the sole 108. An adjustable closure panel 106 extends across an opening in a top portion of the upper 110. Collectively, the sole 108, the upper 110, and the closure panel 106 define an interior foot compartment for receiving the foot of a cyclist. The upper 110 and the closure panel 106 also collectively define an opening 112 for a foot in the top portion of the cycling shoe 100 into the foot compartment. During use, a cyclist can slide his or her foot through the opening 112 and into the foot compartment to put the shoe on.

The closure panel 106 is adjustable by virtue of the fact that at least part of the closure panel 106 is movable with respect to the upper 110 to increase or decrease the size of the opening 112 into the foot compartment. In some implementations, a portion of the closure panel 106 (e.g., the front end, or the front end and one or more of the sides) may be physically attached (e.g., with stitching, adhesive, or the like) to the upper 110, but the portion of the closure panel 106 at and/or near the edge of the opening 112 is not connected to the upper 110, but instead, is free to move away from or closer to the upper 110, at least somewhat, unless restrained, for example, by the shoe's closure mechanism when the shoe is closed (as in FIGS. 1-3).

The lever assembly 104, which is exposed at an outer, rear surface of the upper 110, is movable about a hinge 114 between a first position (e.g., closed, see FIGS. 1-3) and a second position (e.g., open, see FIG. 4). In general, moving the lever assembly 104 from the first position (closed, FIGS. 1-3) to the second position (open, FIG. 4) loosens the shoe's closure mechanism, which allows at least part of the closure panel 106 to be moved away from the upper 110 thereby loosening, or opening, the shoe and increasing the size of the opening 112. In general, moving the lever assembly 104 from the second position (open, FIG. 4) to the first position (closed, FIGS. 1-3) tightens the shoe's closure mechanism, which pulls at least a portion of the closure panel 106 toward the upper 110 to tighten, or close, the shoe 100.

In the illustrated implementation, the lever assembly 104 is configured such that in the first position (closed, FIGS. 1-3), the lever assembly 104 substantially conforms to a contour of the rear surface of the upper 110. The rear surface 20 of the upper 110 in the illustrated implementation has a profile that is curved and convex. In this regard, the lever assembly 104 has a pivoting support arm 138 with an outer, rear-facing surface that has a profile that is similarly curved and convex. The pivoting support arm 138 in the illustrated 25 implementation is a rigid structure, which may be made of metal or plastic or the like, that is attached to and pivots about the hinge 114 and that physically supports other 30 elements of the lever assembly 104. In a typical implementation, the fact that the lever assembly 104, in the first position (closed, FIGS. 1-3), substantially conforms to the contour of the rear surface of the upper 110, as shown in FIGS. 1 and 2, for example, helps contribute to the overall aerodynamic nature of the shoe 100.

In the second position (open, FIG. 4), the lever assembly 35 104 extends away from the upper 110 in a rearward direction from the rear surface of the upper 110. In a typical implementation, the lever assembly 104 swings at least 90 degrees between the closed position (FIGS. 1-3) and a fully open 40 position (FIG. 4). In some implementations, of course, the swing can be less than or greater than 90 degrees.

In the illustrated implementation, there is one, and only 45 one, cable 116 that extends between the lever assembly 104 and the closure panel 106. This cable 116 is configured such that it becomes loose when the lever assembly 104 is moved from the first position (closed, FIGS. 1-3) to the second position (open, FIG. 4), and becomes taut or tight when the lever assembly 104 moves from the second position (open, FIG. 4) to the first position (closed, FIGS. 1-3).

The cable 116, in the illustrated implementation, is routed 50 as follows.

A first end of the cable 116 is attached to a first cable connector 118a at a first lateral edge 120a of the closure panel 106. In this regard, the first end of the cable 116 forms a loop that extends over, or passes through a passage defined 55 within, the first cable connector 118a. The first cable connector 118a can take any one of a variety of possible forms. Generally speaking, the first cable connector 118a is a physical component or element, to which the cable 116 can be connected (e.g., tied, adhered, looped around, passed 60 through, etc.). In the illustrated implementation, the first cable connector 118a is a rigid physical component that defines a roughly semi-circular passage, through which the cable 116 can pass. The first cable connector 118a is attached to the side of the closure panel 106 by a small flap of 65 material. In the illustrated implementation, the first end of the cable 116 is shown having been passed through the roughly semi-circular passage of the first cable connector

118a, with the very end of the cable 116 connected to the cable 116 (e.g., by twisting or crimping) to form a loop.

The second cable connector 118b (at an opposite side of the closure panel 106 from the first cable connector 118a) is substantially the same as the first cable connector 118a (see FIG. 2). In some implementations, however, the second cable connector 118b may be different from the first cable connector 118a, or may be omitted from the shoe 100 entirely.

From the loop (that engages the first cable connector 118a, see FIG. 1), the cable 116 extends in a downward, and rearward direction to a first hole 122 in a first lateral side surface 124a of the projection portion 102 of the shoe 100. The cable 116 enters the first hole 122 and extends through a first passage in the projection portion 102 of the shoe 100. The cable 116 exits the first passage at the rear of the shoe 100 through a second hole 126 (see FIG. 3) in a rear portion 125 of the projection portion 102 of the shoe 100. The cable 116 then extends in a roughly upward direction from the second hole 126 to a cable carriage 128 on the lever assembly 104.

The cable carriage 128 can take any one of a variety of possible forms. Generally speaking, the cable carriage 128 is a physical component or element, to which the cable 116 can be connected (e.g., tied, adhered, looped around, passed through, etc.). In the illustrated implementation, the cable carriage 128 is a rigid physical component that is coupled to, and supported by, the pivoting support arm 138. The illustrated cable carriage 128 has a housing with surfaces that define three, substantially parallel holes that extend through the cable carriage 128 from a bottom surface of the cable carriage 128 to a top surface of the cable carriage 128. Two of the holes are cable holes and are sized and intended to accommodate a cable (e.g., 116) passing through them. The other hole is a threaded hole that is sized and intended to accommodate a threaded rod (146 in FIG. 3). In the illustrated implementation, the cable 116 is shown having been passed up through a first one of the cable holes, across the top of the cable carriage 128, and down through a second one of the cable holes.

The cable 116 extends from the cable carriage 128 in a roughly downward direction toward a third hole 134 in the projection portion 102 of the shoe 100. The cable 116 enters the third hole 134 and extends through a second passage in the projection portion 102 of the shoe 100. The cable 116 exits the second passage through a fourth hole 136 (see FIG. 2) at a second lateral side surface 124b (opposite the first lateral side surface 124a) of the projection portion 102 of the shoe 100. The cable 116 then extends, in an upward and forward direction toward the second cable connector 118b at a second lateral edge 120b (opposite the first lateral edge 120a) of the closure panel 106. The cable 116 is attached to the second cable connector 118b in the same way that the cable 116 is attached to the first cable connector 118a.

The first and second passages through the projection portion 102 of the shoe 100 are entirely contained within the projection portion 102 of the shoe 100 and sized to accommodate the cable 116 in a manner that allows the cable 116 to slide through it with ease. The cable is only securely fastened at its ends—to the cable connectors 118a, 118b at opposite sides of the closure panel 106. Otherwise, the cable is free to slide or move along its path through and around the shoe 100.

There are, of course, other ways that a cable, or cables, may be coupled to and routed through the shoe 100.

The shoe's closure mechanism, in the illustrated implementation, includes the adjustable closure panel 106 (with the cable connectors), the cable 116, and the lever assembly 104.

5 The lever assembly 104 (see, e.g., FIG. 3), in the illustrated implementation, includes the cable carriage 128, a guide 148 for the cable carriage 128, an adjuster 142 for the cable carriage 128, and the pivoting support arm 138 that directly or indirectly supports the other components of the

10 lever assembly 104.

The pivoting support arm 138 is coupled to the hinge 114 and configured to pivot about an axis defined by the hinge 114. The hinge 114 in the illustrated implementation is a split hinge, meaning that the hinge 114 has two hinge portions that are not physically connected to one another (e.g., by a straight shaft or the like). The hinge 114 is supported by an extension 115 off a rear portion of the upper 110, with one portion of the hinge 114 being at a first lateral side of the extension 115 and the other portion of the hinge 114 being closer to a second lateral side of the extension 115 (opposite the first lateral side). In a typical implementation, the extension 115 includes one or more rigid (e.g., plastic) pieces that are attached to the upper 110 via adhesive or other method. With the shoe 100 oriented in a substantially horizontal plane, the axis of the hinge 114 extends in a substantially horizontal direction from one hinge portion to the other across the back of the shoe 100 (see FIG. 3).

According to the illustrated implementation, one portion of the hinge 114 is attached to and supports a first portion 30 138a of the pivoting support arm 138, and the other portion of the hinge 114 is attached to and supports a second portion 138b of the pivoting support arm 138. Collectively, the two portions of the hinge 114 allow the pivoting support arm 138 to pivot about its axis. There is an empty space between the 35 two portions of the hinge 114 (and between the first portion 138a of the pivoting support arm 138 and the second portion 138b of the pivoting support arm 138). The empty space lets the portions of the cable 116 that extend from the cable carriage 128 to the second and third holes 126, 134 to move 40 through the empty space, without physically contacting any other portion of the shoe, as the pivoting support arm 138 pivots about hinge 114. Thus, the portions of the cable 116 that extend from the cable carriage 128 to the second and third holes 126, 134 can remain straight regardless of 45 whether the lever assembly 104 is in a closed position (FIGS. 1-3) or an open position (FIG. 4).

In the illustrated implementation, the first portion 138a and second portion 138b of the pivoting support arm 138 are parallel and substantially mirror images of each other. It is 50 not, however, a requirement that the first portion 138a and the second portion 138b of the pivoting support arm 138 be parallel or substantially mirror images of each other. In some implementations, the pivoting support arm 138 is a more complicated shape and the two sides are not mirror images, 55 and while important invisible axes of the two sides may be parallel to each other, it is perhaps not apparent to most observers because of the complexity of the shape.

In the illustrated implementation, the first portion 138a is a rigid structure that extends from a first portion of the hinge 60 114 in a direction that is substantially upward (when the shoe 100 is closed, FIGS. 1-3) but substantially rearward (when the shoe is in the open position represented by FIG. 4). The second portion 138b, is similarly a rigid structure that extends from a second portion of the hinge 114 in a direction 65 that is substantially upward (when the shoe 100 is closed, FIGS. 1-3) but substantially rearward (when the shoe is in the open position represented by FIG. 4).

The first portion 138a of the pivoting support arm 138 and the second portion 138b of the pivoting support arm 138 are connected together at a distal end thereof by a connector 140 and, therefore, move as one about the axis defined by the hinge 114.

According to the illustrated implementation, the guide 148 for the cable carriage 128 has a pair of tracks that are formed on respective surfaces of the first and second portions 138a, 138b of the pivoting support arm 138 and that face each other. Each track is configured to engage, or extend into, a corresponding recess on one of the side surfaces of the cable carriage 128. With this configuration, the cable carriage 128 is supported by the guide 148, but able to slide along the tracks of the guide 148.

The adjuster 142 for the cable carriage 128 in the illustrated implementation has a knob 144 and a threaded rod 146 that extends from the knob 144. The knob 144 is positioned at the distal end of the lever assembly 104 and the threaded rod extends from the knob 144 through an opening in the connector 140 (or bracket) and through the threaded hole in the cable carriage 128. The adjuster 142 is configured such that it can be rotated about its axis (e.g., by gripping and turning the knob 144) but remains substantially fixed in an axial direction relative to the pivoting support arm 138, for example. The threads on the threaded rod 146 engage the threads of the threaded hole in the cable carriage 128. Thus, when the adjuster is rotated, the engagement between the threads on the threaded rod 146 and the threads in the threaded hole of the cable carriage 128 causes the cable carriage 128 to move along guide 148 (e.g., its tracks) in a depending that depends on the direction of rotation.

Referring to FIG. 3, if the cable carriage 128 is moved in an upward direction (i.e., toward the distal end of its track), then the cable 116 will become more taut, or tighter. Conversely, if the cable carriage 128 is moved in a downward direction (i.e., toward a proximate end of its track), then the cable 116 will become looser. In this manner, the adjuster 142 may be considered a tension adjuster.

The cycling shoe 100 may be sold with or without cable(s) attached to the shoe 100. Either way, the cable(s) will need to be installed on the shoe 100 (either before or after being sold), and over time the cable(s) will need to be replaced. In a typical implementation, before installing a cable on the shoe 100, the cyclist, for example, might manipulate the knob 144 of the tension adjuster 142 to move the cable carriage 128 as close to the bottom (proximate portion) of its guide (or track) as possible. The cyclist also may move the lever assembly 104 to an open position (see, e.g., FIG. 4).

Then, the cyclist may pass one end of the cable 116 through or around the first cable connector 118a and create a loop at that end of the cable 116 (e.g., by twisting or crimping) to ensure that the cable 116 remains secured to the first cable connector 118a. Then, the cyclist may pass the cable 116 through the first passage in the projection portion 102 of the shoe 100 to the rear of the shoe 100. Then, the cyclist may pass the cable 116 through a first one of the cable holes in the cable carriage 128, and back through a second one of the cable holes in the cable carriage. Then, the cyclist may pass the cable 116 through the second passage in the projection portion 102 of the shoe 100 toward the front of the shoe 100. Then, the cyclist may pass the leading end of the cable 116 through or around the second cable connector 118a and create a loop at that end of the cable 116 (e.g., by twisting or crimping) to ensure that the cable 116 remains secured to the second cable connector 118a.

At this point, the cable 116 may be, and probably will be, a bit looser than ideal. If so, then the cyclist may manipulate

the knob 144 of the tension adjuster 142 to move the cable carriage 128 toward the distal end of the lever assembly 104 thereby tightening the cable 116. The desired tightness may be one where the shoe 100 will be tight enough when the lever assembly 104 is flipped up into the closed position, but loose enough to allow putting the shoe on and off when the lever assembly 104 is flipped down into the open position.

FIGS. 5-7 show an implementation of a cycling shoe 500 that is similar to the cycling shoe 100 of FIG. 1.

In this regard, the cycling shoe 500 has a sole 508 and an upper 510 attached to the sole 508. An adjustable closure panel 506 extends across an opening in a top portion of the upper 510. Collectively, the sole 508, the upper 510, and the closure panel 506 define an interior foot compartment for receiving the foot of a cyclist. The upper 510 and the closure panel 506 also collectively define the opening 512 for a foot in the top portion of the cycling shoe 500 into the foot compartment. During use, a cyclist can slide his or her foot through the opening 512 and into the foot compartment to put the shoe on. The cycling shoe 500 has a closure mechanism that includes the adjustable closure panel 506 (with cable connectors), a cable 516, and a lever assembly 504. The cable 516 passes through passages in a projection portion 502 of the shoe 500 that extends off a bottom of the sole 508 of the shoe 500.

A notable difference between the cycling shoe 500 of FIGS. 5 and 6 and the cycling shoe 100 of FIG. 1 is that the cycling shoe 500 of FIGS. 5 and 6 is fitted with a strip 550 of semi-rigid, but flexible material that is attached (e.g., with adhesive, stitching, etc.) to opposite lateral side surfaces of the shoe 500 and that extends past to the opening of the upper 510 and contact a portion of the closure panel 506 that extends over the upper 510. Thus, each strip 550 is configured to urge the opening of the upper to be more open and the closure panel 506 at the top of the shoe 500 away from the upper 510 so that when the shoe is open (as in FIGS. 5 and 6), the closure panel 506 is pushed away from the upper 510, making the opening 512 for the foot larger than it otherwise might be. This enables the cyclist to easily slip his or her foot inside the shoe when the shoe 500 is open and minimizes the risk that the adjustable closure panel 506 might interfere with cyclist's efforts in this regard.

The material, specific configuration (e.g., length, width, thickness, location), and performance characteristics of each strip 550 can vary. In some implementations, the material, width and thickness of each strip 550 is such that, if supported as a cantilever with 500 g of mass hung 50 millimeters from the fixed end, the end will deflect in the range of 9 millimeters to 30 millimeters. This characteristic can be achieved using a variety of materials. A stiff material such as carbon fiber can be used if the cross-sectional area of the piece to be glued, or otherwise attached, to the shoe is relatively small. A less stiff material such as a non-reinforced plastic can obtain the same result with a larger cross-sectional area.

FIG. 8 shows another implementation of a cycling shoe 800 that is similar to the cycling shoe 100 of FIG. 1.

In this regard, the cycling shoe 800 has a sole 808 and an upper 810 attached to the sole 808. An adjustable closure panel 806 extends across an opening in a top portion of the upper 810. Collectively, the sole 808, the upper 810, and the closure panel 806 define an interior foot compartment for receiving the foot of a cyclist. The upper 810 and the closure panel 806 also collectively define an opening 812 for a foot in the top portion of the cycling shoe 800 into the foot compartment. During use, a cyclist can slide his or her foot through the opening 812 and into the foot compartment to

11

put the shoe on. The cycling shoe 800 has a closure mechanism that includes the adjustable closure panel 806 (with cable connectors), a cable 816, and a lever assembly 804 (shown in the closed position in FIG. 8). The cycling shoe 800 of FIG. 8 also has a projection portion 802, like the projection portion 102 in FIGS. 1-4.

The cable 816 in the shoe 800 of FIG. 8 is routed differently than the cable 116 in the shoe 100 of FIGS. 1-4. More specifically, the cable 816 in the shoe 800 of FIG. 8 does not pass through the projection portion 802 of the shoe 800. Instead, the cable 816 in the shoe 800 of FIG. 8 extends from the cable connector along an outer side surface of the shoe in a rearward direction, through an opening between the upper 810 and the extension 815 at the rear of the shoe 800, and to the lever assembly 804. In a typical implementation, the side of the shoe 800 opposite the one shown in FIG. 8 would be a mirror image of FIG. 8.

Even though the cable 816 in the shoe 800 of FIG. 8 does not pass through the projection portion 802 of the shoe 800, the shoe 800 still has a projection portion 802. As discussed elsewhere, herein, the projection portion 802 of the shoe 800 helps make the overall shoe 800 more aerodynamic, especially when in a toe-down configuration.

Referring again to FIGS. 1-4, the projection portion 102 on the bottom of the cycling shoe 100 has a particular shape and position that contributes to the shoe's 100 overall aerodynamic nature. The projection portion 102 in the illustrated implementation extends off a bottom surface of the sole 108 of the cycling shoe 100 behind a cleat portion of the sole 108 (i.e., a portion of the sole 108 that can accommodate the cycling cleat 152). In a typical implementation, the cycling cleat 152 engages the sole 108 of the cycling shoe 100 via an attachment means (e.g., one or more screw holes in the bottom of the sole 108 that are can receive screws or the like that hold the cleat onto the sole 108). Moreover, in some implementations (see, e.g., FIG. 1), when a cleat is attached to the sole of the shoe 100, there is a space (of at least 3 millimeters) between the rear-most surface of the cleat and the forward-most surface of the projection portion 102. However, in some implementations, there are types of cleats where no space would be required or present.

In the illustrated implementation, the projection portion 102 has surfaces that roughly define a first lateral side surface 124a, a second lateral side surface 124b at an opposite side of the cycling shoe 100 from the first lateral side surface, a front side surface 124c, a rear side surface 124d, and a bottom surface 124e. The bottom surface 124e extends between and connects the side surfaces, including the first lateral side surface 124a, the second lateral side surface 124b, the front side surface 124c, and the rear side surface 124d. Rounded lateral edges 124f, 124g (see FIG. 3 and FIG. 10) connect each of the first and second lateral side surfaces 124a, 124b to the bottom surface 124e. These rounded lateral edges 124f, 124g give the shoe 100 a highly aerodynamic profile, particularly when the shoe 100 is on a pedal in a toe-down configuration (i.e., with the toes pointed down toward the ground, as shown in FIG. 9).

FIG. 9 shows a schematic representation of cycling shoe 100 on the foot of a cyclist. There is a cleat 930 attached to the sole of the cycling shoe 100 in a cleat portion of the sole. The cleat 930 is engaged with the pedal 932 of a bicycle, not shown, and the cyclist's foot is in a toe-down configuration (i.e., pointing toward the ground). The bicycle is moving in the direction of arrow M, which results in air resistance (caused by air, or "apparent wind," moving toward and around the shoe 100 in a direction A, opposite direction M).

12

With the shoe 100 configured as shown, the projection portion 102 off the sole 108 is at a backside of the shoe 100 relative to the cyclist's motion. Therefore, the air moving in direction A, flows around the lateral side edges of the shoe 100, the lateral side surfaces 124a, 124b of the projection portion 102a, and the rounded lateral edges 124f, 124g of the projection portion 102 and, finally, behind the shoe 100. The applicant has discovered that the overall shoe 100 configuration, and particularly the rounded lateral edges 124f, 124g of the projection portion 102a, reduces air turbulence behind the shoe when in a toe down configuration (as in FIG. 9). This design reduces aerodynamic drag while the foot is in a toe-down position (as shown in FIG. 9) while cycling.

FIG. 10 is a cross-sectional view of the shoe 100 of FIG. 9 taken along line A-A. Again, the projection portion 102 is shown at a backside of the shoe 100 relative to the cyclist's motion so that, as the cyclist moves (in direction M), the air moves (in direction A) around the lateral sides of the shoe 100, past the rounded lateral edges 124f, 124g of the projection portion 102 and, finally, behind the shoe 100. The lateral side surfaces 124a, 124b of the projection portion 102a, and the rounded lateral edges 124f, 124g of the projection portion 102 are labeled. Again, arrow M shows the direction of cyclist motion, and arrow A shows the direction of apparent wind toward the shoe 100.

FIGS. 11 and 12 show a schematic representation of the shoe 100 on the foot of a cyclist who is riding in direction M in a toe-down configuration. The apparent wind A encounters the top of the foot, separates to go around the sides of the foot and then comes back together smoothly and gradually behind the flat sole of the shoe. This design results in very low turbulence behind the shoe, and low drag while the cyclist is riding.

When the shoe 100 is in a toe-down position (as shown), the shape of the sole is such that the cross section of the shoe 100 in the plane of the wind direction is such that the trailing edge of the shoe is rounded rather than substantially flat. It is rounded in a concave shape. The furthest point of the trailing edge of the shoe in a 55-degree toe-down position is about 22 mm from where the flat sole of a conventional sole would be (if the projection portion were not present). Viable variations from this dimension can range from 14 mm to greater than 47 mm. In some implementations, the range might be between 17 mm and 37 mm. (see, e.g., FIG. 10). In a typical implementation, each rounded lateral edges of the projection portion has a radius of no less than 7 mm; in an exemplary implementation, the radius is between about 10 mm and 50 mm.

For comparison purposes, FIGS. 13 and 14 show a schematic representation of a shoe with a flat bottom (and no projection portion) on the foot of a cyclist who is riding in direction M in a toe-down configuration. The apparent wind A encounters the top of the foot, separates to go around the sides of the foot and then comes back together rather turbulently behind the flat sole of the shoe. This design produces a great deal of turbulence behind the shoe, and the cyclist will experience a great deal of drag while riding.

Computational fluid dynamics simulations confirm that, in a typical implementation, the design(s) disclosed herein method produce(s) the advantages mentioned herein and also provide good visualization of the improvement in airflow.

FIGS. 15 and 16, for example, show computational fluid dynamics simulations of one shoe (like the one in FIG. 1) that includes a projection portion (FIG. 15), and a different shoe (without a projection portion) (FIG. 16), both in a toe down configuration, moving and experiencing a resulting

apparent wind. The condition (e.g., the speed of the apparent wind) in both simulations is identical. From these simulations, it can be seen that the amount of turbulence behind the FIG. 16 (no projection portion) shoe is far greater than the amount of turbulence behind the FIG. 15 (projection portion) shoe.

Likewise, FIGS. 17 and 18 show computational fluid dynamics simulations of one shoe (like the one in FIG. 1) that includes a projection portion (FIG. 17), and a different shoe (without a projection portion) (FIG. 18), both in a toe down configuration, moving and experiencing a resulting apparent wind. The condition (e.g., the speed of the apparent wind) in both simulations is identical. From these simulations, it can be seen that the amount of turbulence behind the FIG. 18 (no projection portion) shoe is far greater than the amount of turbulence behind the FIG. 17 (projection portion) shoe—this is evident from the less swirling of streamlines in FIG. 17 than in FIG. 18. Moreover, the air velocity behind the trailing edge of the shoe is higher in the FIG. 17 (projection portion) shoe as compared to the FIG. 18 (no projection portion) shoe.

FIGS. 19 and 20 show computational fluid dynamics simulations that are similar to those in FIGS. 15 and 16, just from a different perspective, and showing kinetic energy. In particular, FIGS. 19 and 20 show one shoe (like the one in FIG. 1) that includes a projection portion (FIG. 19), and a different shoe (without a projection portion) (FIG. 20), both in a toe down configuration, moving and experiencing a resulting apparent wind. The condition (e.g., the speed of the apparent wind) in both simulations is identical. From these simulations, it can be seen that the FIG. 20 (no projection portion) shoe in the upper image shows a lot more kinetic energy imparted to the air, thus creating more drag.

A number of embodiments of the invention have been described. Nevertheless, it will be understood that various modifications may be made without departing from the spirit and scope of the invention.

For example, the size, shape, and configuration, relative and absolute, of the various cycling shoe components can vary considerably. A variety of materials can be used to form the cycling shoe and/or its various components.

There are a variety of ways that the cable (or cables) may be routed through or around the cycling shoe. For example, in some implementations, the cycling shoe may be fit with two cables: one extending from a first one of the cable connectors to the lever assembly, and another extending from the other of the cable connectors to the lever assembly. The routing of the cable (or cables) through the shoe can include one or more passages that are not expressly disclosed herein. These passage(s) may be through the sole of the shoe, the upper, the projection, and/or any other portions of the shoe.

The configuration of the lever assembly can vary. For example, the cable carriage can be virtually any kind of physical component (e.g., an anchor, or the like) whose position within the lever assembly can be adjusted, and to whom a cable can be connected. The tension adjuster can be virtually any kind of mechanism that enables a user to adjust the position of the cable carriage. The tension adjuster may be lockable in its final, adjusted position. The guides for the cable carriage and the manner in which the cable carriage engages the guides can vary. For example, the guides may be recesses and the cable carriage may include projections that extend into and that can slide along the recesses.

The cable connectors can be any kind of physical structure, to which the cable(s) can be attached. In fact, in some implementations, the cable connectors may be a simple

eyelet hole in the closure panel (or in a piece of fabric attached to the closure panel) that may be reinforced with a metal or plastic grommet, for example. The cable connectors can be attached to the closure panel in any number of a variety of possible ways, or can be integrally formed with the closure panel. Moreover, some implementations may include only one cable connector (at one lateral side of the closure panel), where the opposite side of the closure panel is securely connected to the upper.

10 Any number of strips of material may be provided to urge the closure panel away from the upper. In this regard, some shoes may have only one such strip of material, some may have two strips of material (one on each side of the shoe, or two on one side of the shoe), some may have more than two 15 strips of material, and the strips of material may be configured in any number of possible ways.

The extension 115 is typically a separate, rigid piece of material that is attached to (e.g., via adhesive or some other connection technique) to a rear part of the upper. In some 20 implementations, the extension can be integrally formed with the upper. The extension can have any one of a variety of possible shapes or sizes. The shape and size disclosed in the figures and described herein generally contributes to the overall aerodynamic nature of the shoe.

25 The projection portion is described herein as a portion of the sole of the shoe. The protection portion may, in some implementations, be integrally formed with the sole, or may, in some implementations, be separately formed, but attached to the sole.

30 The phrase “toe down configuration,” and the like are used herein. Generally speaking, this phrase refers to any configuration in which the toe of the shoe is pointing in a downward direction (e.g., toward the surface on which the cyclist is riding). This can include, of course, configurations 35 where the angle created by the intersection of the direction of the front of the shoe and the surface being ridden on is greater than about 45 degrees (e.g., about 55 degrees as shown in FIGS. 9 and 10).

In a typical implementation, each lateral side surface of 40 the projection portion extends from a bottom surface of the sole flush with (or very close to flush with) a corresponding lateral side surface of the sole. As used herein, the phrase very close to flush can include an offset of up to about $\frac{1}{8}$ of an inch. So, in a typical implementation, the lateral side 45 surface of the sole and the lateral side surface of the projection portion are flush or have an offset of no more than about $\frac{1}{8}$ of an inch. Likewise, in a typical implementation, the lateral side surface of the sole is flush with (or, again, very close to flush with) a corresponding lateral side surface of the upper. In some implementations, the projection portion is integral with the sole (i.e., formed as a single structure with the sole and not separable from the sole without destroying the projection portion, the sole, or both).

In a typical implementation, the projection portion has a 55 rear surface that slopes gently upward from the bottom surface of the projection portion to a rear of the sole/upper. In a typical implementation, the rear surface of the projection portion, too, is flush with (or very close to flush with) a corresponding rear surface of the sole and/or upper.

60 In some implementations, the lateral side surfaces are substantially flat. In some implementations, however, each lateral side surface is curved so as to form, together with its corresponding rounded lateral edge, a single, continuous curved or rounded surface that extends from the sole of the shoe to the bottom surface of the projection portion. In some implementations, the bottom surface of the projection portion can be similarly curved.

15

A variety of terminology is used herein to describe relative positions and orientations. This terminology, including for example "up", "down", "forward", "rearward", "top", "bottom," etc., is solely for the purposes of clarity and is not intended to limit the scope of what is described here or to require particular positions and/or orientations. Accordingly, such relative terminology should not be construed to limit the scope of the present application. Additionally, the term substantially, and similar words, such as substantial, are used herein. Unless otherwise indicated, substantially, and similar words, should be construed broadly to mean completely and almost completely. 5

While this specification contains many specific implementation details, these should not be construed as limitations on the scope of any inventions or of what may be claimed, but rather as descriptions of features specific to particular embodiments of particular inventions. Certain features that are described in this specification in the context of separate embodiments can also be implemented in combination in a single embodiment. Conversely, various features that are described in the context of a single embodiment can also be implemented in multiple embodiments separately or in any suitable subcombination. Moreover, although features may be described above as acting in certain combinations and even initially claimed as such, one or more features from a claimed combination can in some cases be excised from the combination, and the claimed combination may be directed to a subcombination or variation of a subcombination. 10

Other implementations are within the scope of the claims.

What is claimed is:

1. An assembly comprising:

a cycling shoe comprising:

a sole comprising a bottom surface that defines part of an exterior bottom surface of the cycling shoe; 35 screw holes in the sole with openings that are exposed at the bottom surface of the sole, wherein each screw hole is configured to receive and engage a screw that holds a cycling cleat onto the bottom surface of the sole;

an upper attached to the sole to define an interior space between the upper and the sole, wherein the upper has an edge that defines and completely surrounds an opening in the upper, wherein the opening provides access from outside the cycling shoe into the interior space; 45

an adjustable closure panel outside of the interior space and extended across a portion of the opening in the upper to cover the portion of the opening in the upper; and

a lever assembly exposed at an outer, rear surface of the upper, wherein the lever assembly is movable about a hinge between a first position and a second position; and

one or more passages through a projection portion of the sole of the cycling shoe to accommodate one or more cables for connecting the lever assembly to the adjustable closure panel, 55

one or more cables passing through the one or more passages, wherein the one or more cables are connected to the lever assembly and to the adjustable closure panel via a cable connector at each respective one the first and second lateral edges of the adjustable closure panel;

wherein the lever assembly is configured such that moving the lever assembly between the first position and the second position causes the one or more 60

16

cables-connected between the lever assembly and the adjustable closure panel, to tighten or loosen the closure panel relative to the upper, and wherein loosening the one or more cables that connect the lever assembly to the adjustable closure panel facilitates lifting the adjustable closure panel from a first location to a second location, wherein the adjustable closure panel is further away from the upper in the second location than in the first location, so that a foot can be inserted or removed from the cycling shoe,

wherein each of the one or more cables extends through the projection portion of the sole of the cycling shoe between the lever assembly and the adjustable closure panel, and

wherein the projection portion extends off a bottom surface of the cycling shoe behind a cleat portion of the sole.

2. The cycling shoe of claim 1, wherein the lever assembly is configured such that:

in the first position, the lever assembly substantially conforms to a contour of the rear surface of the upper, and

in the second position, the lever assembly extends away from the upper in a rearward direction from the rear surface of the upper.

3. The cycling shoe of claim 1, wherein each of the one or more cables extends from the lever assembly, into a rear hole in a rear portion of the projection portion, through the projection portion, to a forward hole in a side surface of the projection portion, and to the closure panel.

4. The cycling shoe of claim 1, wherein the projection portion comprises:

a first lateral side surface; 35 a second lateral side surface at an opposite side of the cycling shoe from the first lateral side surface; a bottom surface; and rounded lateral edges that connect each of the first and second lateral side surfaces to the bottom surface.

5. The cycling shoe of claim 1, wherein the lever assembly comprises a cable carriage for coupling the one or more cables to the lever assembly.

6. The cycling shoe of claim 5, wherein the cable carriage defines one or more openings, or anchors, through which the one or more cables can pass or to which the one or more cables can be attached, to become coupled to the lever assembly.

7. The cycling shoe of claim 6, wherein the cable carriage further comprises:

a guide that extends along the lever assembly between a proximal part of the lever assembly and a distal part of the lever assembly, wherein the cable carriage is coupled to and is movable along the guide between the proximal part of the lever assembly and the distal part of the lever assembly.

8. The cycling shoe of claim 7, wherein the lever assembly further comprises:

a tension adjuster for adjusting a position of the cable carriage along the guide, wherein the tension adjuster comprises a knob and a threaded rod that are supported by a bracket portion of the lever assembly in a manner that permits the tension adjuster to be rotated about an axis but prevents the adjuster from being moved in an axial direction.

9. The cycling shoe of claim 8, wherein the cable carriage has surfaces that define a threaded hole through the cable carriage, and

17

wherein the threaded rod of the tension adjuster passes through the threaded hole of the cable carriage.

10. The cycling shoe of claim 8, further comprising one or more cables connecting the lever assembly to the adjustable closure panel.

11. The cycling shoe of claim 10, wherein the one or more cables include one, and only one, cable,

wherein the one, and only one, cable extends from a first cable connector at a first lateral edge of the closure panel, through a first one of the passages, through a first cable hole in the cable carriage, through a second cable hole in the cable carriage, through a second one of the passages, and to a second cable connector at a second lateral edge of the closure panel, opposite the first lateral edge of the closure panel.

12. The cycling shoe of claim 10, wherein the one or more cables include a first cable and a second cable,

wherein the first cable extends from a first cable connector at a first lateral edge of the closure panel, through a first one of the passages, and to the cable carriage, and wherein the second cable extends from a second cable connector at a second lateral edge of the closure panel opposite the first lateral edge of the closure panel, through a second one of the passages, and to the cable carriage.

13. The cycling shoe of claim 10, wherein the hinge comprises:

a first portion that connects a first part of the lever assembly to a first lateral portion of the upper; and a second portion that connects a second part of the lever assembly to a second lateral portion of the upper, wherein the first portion of the hinge is separated from the second portion of the hinge by a space, and wherein the cycling shoe is configured such that the one or more cables pass through the space when lever assembly moves between the first position and the second position.

14. A cycling shoe comprising:

a sole and an upper attached to the sole, wherein the sole comprises a bottom surface that defines part of an exterior bottom surface of the cycling shoe; screw holes in the sole with openings that are exposed at the bottom surface of the sole, wherein each screw hole is configured to receive and engage a screw to hold a cycling cleat onto the bottom surface of the sole at a cleat portion of the sole;

a projection portion that extends off a bottom surface of the shoe behind the cleat portion of the sole;

an adjustable closure panel that extends across an opening in the upper; and

a lever assembly exposed at an outer, rear surface of the upper, wherein the lever assembly is movable about a hinge between a first position and a second position; and

one or more passages through the projection portion of the cycling shoe, wherein each passage comprises:

a rear opening on a heel end of the projection portion of the cycling shoe at least half a length of the lever assembly below the hinge of the lever assembly, wherein the position of the rear opening remains constant with respect to the hinge regardless of whether the lever assembly is in the first position or the second position, and

a front opening in the projection portion near a middle to rear third of a side of the cycling shoe and lower than the closure panel,

18

wherein the one or more passages accommodate one or more cables for connecting the lever assembly to the adjustable closure panel,

one or more cables passing through the one or more passages and connecting the lever assembly to the adjustable closure panel;

wherein the lever assembly is configured such that moving the lever assembly between the first position and the second position causes the one or more cables, if connected between the lever assembly and the adjustable closure panel, to tighten or loosen the closure panel relative to the upper, and the lever assembly is configured to work as an over-center mechanism to hold the lever assembly in place when it is in the first position and tightening the closure panel against a foot, wherein each of the one or more cables extends through the projection portion of the sole of the cycling shoe, and

wherein loosening the one or more cables that connect the lever assembly to the adjustable closure panel facilitates lifting the closure panel away from the upper so that a foot can be inserted or removed from the cycling shoe.

15. The cycling shoe of claim 14, wherein the projection portion that extends off the bottom surface of the shoe behind a cleat portion of the sole, wherein the projection portion comprises:

a first lateral side surface; a second lateral side surface at an opposite side of the cycling shoe from the first lateral side surface; a bottom surface; and rounded lateral edges that connect each of the first and second lateral side surfaces to the bottom surface.

16. A cycling shoe comprising:

a sole wherein the sole comprises a bottom surface that defines part of an exterior bottom surface of the cycling shoe;

screw holes in the sole with openings that are exposed at the bottom surface of the sole, wherein each screw hole is configured to receive and engage a screw to hold a cycling cleat onto the bottom surface of the sole at a cleat portion of the sole;

an upper attached to the sole to define an interior space between the upper and the sole, wherein the upper has an edge that defines and completely surrounds an opening in the upper, wherein the opening provides access from outside the cycling shoe into the interior space;

an adjustable closure panel outside of the interior space and extended across a portion of the opening in the upper to cover the portion of the opening in the upper; and

a lever assembly exposed at an outer, rear surface of the upper, wherein the lever assembly is movable about a hinge between a first position and a second position; and

a projection portion that extends off the exterior bottom surface of the cycling shoe behind the cleat portion of the sole;

one or more passages through the projection portion of the cycling shoe to accommodate one or more cables for connecting the lever assembly to the adjustable closure panel;

one or more cables passing through the one or more passages through the projection portion of the cycling shoe, wherein the one or more cables are connected to

19

the lever assembly and to a cable connector at each respective one of first and second lateral edges of the adjustable closure panel;

wherein the lever assembly is configured such that moving the lever assembly between the first position and the second position causes the one or more cables connected between the lever assembly and the adjustable closure panel, to tighten or loosen the closure panel relative to the upper,

wherein loosening the one or more cables that connect the lever assembly to the adjustable closure panel facilitates lifting the adjustable closure panel from a first location to a second location, wherein the adjustable closure panel is farther away from the upper in the second location than in the first location, so that a foot can be inserted or removed from the cycling shoe, wherein the lever assembly comprises a cable carriage for coupling the one or more cables to the lever assembly, wherein the cable carriage defines one or more openings, or anchors, through which the one or more cables pass or to which the one or more cables are attached, to be coupled to the lever assembly, and

wherein the cable carriage further comprises:

a guide that extends along the lever assembly between a proximal part of the lever assembly and a distal part of the lever assembly,

wherein the cable carriage is coupled to and is movable along the guide between the proximal part of the lever assembly and the distal part of the lever assembly.

17. The cycling shoe of claim 16, further comprising: a strip of material attached to a side surface of the cycling shoe and that extends to the opening of the upper and contacts a portion of the closure panel that extends over the upper,

wherein the strip of material is thereby configured to urge the opening of the upper into a more open position and the closure panel away from the upper so that when the shoe is in an open configuration, the closure panel is pushed away from the upper.

18. The cycling shoe of claim 1, wherein the adjustable closure panel extends across the opening in the upper above the upper.

19. The cycling shoe of claim 1, wherein the guide comprises a track.

20. The cycling shoe of claim 1, wherein the lever assembly comprises:

a cable carriage,
a guide for the cable carriage,

an adjuster for the cable carriage, wherein the adjuster comprises a knob and a threaded rod that extends from the knob; and wherein the threaded rod extends through an opening in a connector or bracket and through a threaded hole in the cable carriage, wherein threads on the threaded rod engage corresponding threads of the threaded hole in the cable carriage; and

a pivoting support arm,
wherein the adjuster is configured to be rotatable about an axis but to remain fixed in an axial direction relative to the pivoting support arm, and wherein the adjuster is

configured such that when the knob of the adjuster is rotated, the engagement between the threads on the threaded rod and the corresponding threads in the threaded hole of the cable carriage causes the cable carriage to move along the guide in an axial direction that depends on the direction of rotation of the knob of the adjuster,

20

wherein moving the lever assembly from the first position to the second position loosens the cycling shoe, which allows at least part of the adjustable closure panel to be moved away from the upper thereby loosening increasing a size of an opening for a foot in the cycling shoe, and

wherein moving the lever assembly from the second position to the first position tightens the cycling shoe, which pulls at least a portion of the adjustable closure panel toward the upper to tighten the cycling shoe.

21. A cycling shoe comprising:

a sole and an upper attached to the sole;
an adjustable closure panel that extends across an opening in the upper; and

a lever assembly exposed at an outer, rear surface of the upper, wherein the lever assembly is movable about a hinge between a first position and a second position; and

one or more passages through the cycling shoe to accommodate one or more cables for connecting the lever assembly to the adjustable closure panel,

wherein the lever assembly is configured such that moving the lever assembly between the first position and the second position causes the one or more cables, if connected between the lever assembly to the adjustable closure panel, to tighten or loosen the closure panel relative to the upper,

wherein the lever assembly comprises a cable carriage for coupling the one or more cables to the lever assembly, wherein the cable carriage defines one or more openings, or anchors, through which the one or more cables can pass or to which the one or more cables can be attached, to become coupled to the lever assembly, and

wherein the cable carriage further comprises:

a guide that extends along the lever assembly between a proximal part of the lever assembly and a distal part of the lever assembly,

wherein the cable carriage is coupled to and is movable along the guide between the proximal part of the lever assembly and the distal part of the lever assembly; further comprising:

a strip of material attached to a side surface of the cycling shoe and that extends to the opening of the upper and contacts a portion of the closure panel that extends over the upper,

wherein the strip of material is thereby configured to urge the opening of the upper into a more open position by pushing the closure panel away from the upper.

22. A cycling shoe comprising:

a sole, wherein the sole comprises a bottom surface that defines part of an exterior bottom surface of the cycling shoe;

screw holes in the sole with openings that are exposed at the bottom surface of the sole, wherein each screw hole is configured to receive and engage a screw to hold a cycling cleat onto the bottom surface of the sole; an upper attached to the sole;

an adjustable closure panel that extends across an opening in the upper; and

a lever assembly exposed at an outer, rear surface of the upper, wherein the lever assembly is movable about a hinge between a first position and a second position; a projection portion that extends off the exterior bottom surface of the cycling shoe behind the cleat portion of the sole; and

21

one or more passages through the projection portion that extends off the exterior bottom surface of the cycling shoe, wherein each of the passages comprises:
 a first opening on a heel end of the projection portion that extends off the exterior bottom surface of the cycling shoe, wherein a position of the first opening remains constant with respect to the hinge regardless of whether the lever assembly is in the first position or the second position or anywhere between the first position and the second position, and
 a second opening in the projection portion near a middle to rear third of a side of the cycling shoe and lower than the closure panel,
 wherein the one or more passages are configured to accommodate one or more cables for connecting the lever assembly to the adjustable closure panel, one or more cables passing through the one or more passages and connecting the lever assembly to the adjustable closure panel;
 wherein the lever assembly is configured such that moving the lever assembly between the first position and the second position causes the one or more cables connected between the lever assembly and the adjustable closure panel, to tighten or loosen the closure panel relative to the upper, and
 wherein loosening the one or more cables that connect the lever assembly to the adjustable closure panel facilitates lifting the closure panel away from the upper so that a foot can be inserted or removed from the cycling shoe.

23. The cycling shoe of claim 22, wherein the first opening of each passage is more than half a length of the lever assembly below the hinge of the lever assembly.

24. The cycling shoe of claim 22, wherein the second opening of each passage is near a middle to rear third of a corresponding one of the lateral side surfaces of the cycling shoe.

25. The cycling shoe of claim 22, wherein the lever assembly is configured to work as an over-center mechanism to hold the lever assembly in place when it is in the first position to tighten the closure panel against a foot.

26. The cycling shoe of claim 22, wherein the second opening is near a middle to rear third of the sides of the cycling shoe.

27. A cycling shoe comprising:
 a sole, wherein the sole comprises a bottom surface that defines part of an exterior bottom surface of the cycling shoe;
 screw holes in the sole with openings that are exposed at the bottom surface of the sole, wherein each screw hole is configured to receive and engage a screw to hold a cycling cleat onto the bottom surface of the sole;
 an upper attached to the sole to define an interior space between the upper and the sole, wherein the upper has a top edge that has a closed shape and defines and completely surrounds an opening in the upper, wherein the opening provides access from outside the cycling shoe into the interior space;
 an adjustable closure panel outside of the interior space and that extends across a portion of the opening in the upper, wherein the adjustable closure panel is movable between a first position held tight against the upper and a second position lifted away from the upper;
 a first cable connector at a first lateral edge of the adjustable closure panel;
 a second cable connector at a second lateral edge of the adjustable closure panel;

a projection portion coupled to, in direct physical contact with, and beneath the sole, wherein the projection portion is located behind a cleat portion of the sole, wherein the projection portion defines:

a first internal passage that extends through the projection portion from a first hole in a first lateral side surface of the projection portion to a second hole at a rear surface of the projection portion; and
 a second internal passage that extends through the projection portion from a third hole in a second lateral side surface of the projection portion to a fourth hole at the rear surface of the projection portion;

an extension at a rear portion of the upper;
 a lever assembly physically coupled to the extension via a hinge at a heel portion of the upper, wherein the lever assembly comprises:

a pivoting support arm, wherein the pivoting support arm is configured to pivot about the hinge, relative to an entirety of the extension and the upper, between a closed position and an open position, wherein the hinge is behind a heel of the cycling shoe;
 a guide formed along the pivoting support arm; and
 a cable carriage in direct physical contact with and movable along the guide;

a cable connected to the first cable connector at the first lateral edge of the adjustable closure panel and to the second cable connector at the second lateral edge of the adjustable closure panel,

wherein the cable extends from the first cable connector at the first lateral edge of the adjustable closure panel to the first hole in the first lateral side surface of the projection portion, through the first hole into the first passage in the projection portion, through the first passage, out of the first passage in the projection portion via the second hole at the rear surface of the projection portion, from the second hole to the cable carriage, from the cable carriage to the fourth hole at the rear surface of the projection portion, through the fourth hole into the second passage, through the second passage, out of the second passage via the third hole in the second lateral side surface of the projection portion, and from the third hole to the second cable connector at the second lateral side surface of the adjustable closure panel,

wherein the lever assembly is configured such that moving the pivoting support arm from the open position to the closed position tightens the cable which causes the cable to pull the adjustable closure panel in a downward direction toward and against the upper, and wherein moving the pivoting support arm from the closed position to the open position loosens the cable facilitating lifting the closure panel away from the upper, and

wherein moving the pivoting support arm of the lever assembly between the open position and the closed position does not change a physical configuration of any portion of the upper or any portion of the sole or a size or shape of the opening defined by the top edge of the upper.

28. A cycling shoe comprising:
 a sole, wherein the sole comprises a bottom surface that defines part of an exterior bottom surface of the cycling shoe;
 screw holes in the sole with openings that are exposed at the bottom surface of the sole, wherein each screw hole

23

is configured to receive and engage a screw to hold a cycling cleat onto the bottom surface of the sole; an upper attached to the sole to define an interior space between the upper and the sole, wherein the upper has a top edge that has a closed shape and defines and completely surrounds an opening in the upper, wherein the opening provides access from outside the cycling shoe into the interior space; an adjustable closure panel outside of the interior space and extended across a portion of the opening in the upper to cover the portion of the opening in the upper; an adjustable closure panel that extends across a portion of the opening in the upper, wherein the adjustable closure panel is movable between a first position held tight against the upper and a second position lifted away from the upper; a first cable connector at a first lateral edge of the adjustable closure panel; a second cable connector at a second lateral edge of the adjustable closure panel; a projection portion coupled to, in direct physical contact with, and beneath the sole, wherein the projection portion is located behind a cleat portion of the sole, wherein the projection portion defines: a first internal passage that extends through the projection portion from a first hole in a first lateral side surface of the projection portion to a second hole at a rear surface of the projection portion; and a second internal passage that extends through the projection portion from a third hole in a second lateral side surface of the projection portion to a fourth hole at the rear surface of the projection portion; an extension at a rear portion of the upper; a lever assembly physically coupled to the extension via a hinge at a heel portion of the upper, wherein the lever assembly comprises: a pivoting support arm, wherein the pivoting support arm is configured to pivot about the hinge, relative to an entirety of the extension and the upper, between a closed position and an open position, wherein the hinge is behind a heel of the cycling shoe; a guide formed along the pivoting support arm; and a cable carriage in direct physical contact with and movable along the guide; a first cable connected to the first cable connector at the first lateral edge of the adjustable closure panel; and a second cable connected to the second cable connector at the second lateral edge of the adjustable closure panel, wherein the first cable extends from the first cable connector at the first lateral edge of the adjustable closure panel to the first hole in the first lateral side surface of the projection portion, through the first hole into the first passage in the projection portion, through the first passage, out of the first passage in the projection portion via the second hole at the rear surface of the projection portion, from the second hole to the cable carriage, wherein the second cable extends from the cable carriage to the fourth hole at the rear surface of the projection portion, through the fourth hole into the second passage, through the second passage, out of the second passage via the third hole in the second lateral side surface of the projection portion, and from the third hole to the second cable connector at the second lateral side surface of the adjustable closure panel,

24

wherein the lever assembly is configured such that moving the pivoting support arm from the open position to the closed position tightens the first and second cables which causes the first and second cables to pull the adjustable closure panel in a downward direction toward and against the upper, and wherein moving the pivoting support arm from the closed position to the open position loosens the cable facilitating lifting the closure panel away from the upper, and wherein moving the pivoting support arm of the lever assembly between the open position and the closed position does not change a physical configuration of any portion of the upper or any portion of the sole or a size or shape of the opening defined by the top edge of the upper.

29. The cycling shoe of claim 1, further comprising: a cycling cleat coupled to a bottom, outer surface of the sole of the cycling shoe, wherein the cycling cleat is configured to engage a pedal on a bicycle.

30. The cycling shoe of claim 29, further comprising: screws engaging the screw holes to hold the cycling cleat in place against the bottom surface of the sole.

31. The cycling shoe of claim 29, wherein the cycling cleat covers a first portion of the bottom surface of the sole but does not cover a second portion of the bottom surface of the sole, wherein the second portion of the bottom surface of the sole that is not covered by the cycling cleat surrounds the first portion of the bottom surface of the sole that is covered by the cycling cleat.

32. The cycling shoe of claim 29, wherein a projection portion is attached to the bottom surface of the sole in a section of the second portion of the bottom surface of the sole and behind the cycling cleat, wherein the projection portion comprises: a first lateral side surface; a second lateral side surface at an opposite side of the cycling shoe from the first lateral side surface; a bottom surface; and rounded lateral edges that connect each of the first and second lateral side surfaces to the bottom surface.

33. The cycling shoe of claim 32, further comprising: a space of at least 3 millimeters between a rear-most surface of the cycling cleat and a forward-most surface of the projection portion.

34. The cycling shoe of claim 1, wherein the upper does not extend beneath an entirety of the closure panel when the closure panel is in a closed position, such that when the closure panel is in the closed position and the shoe is in place on a foot of a user, at least a portion of the closure panel would be in direct physical contact with the foot of the user or in direct contact with a sock of the user, with no portion of the upper, or any other portion of the cycling shoe obstructing that direct physical contact.

35. The cycling shoe of claim 14, further comprising: a cycling cleat coupled to a bottom, outer surface of the sole of the cycling shoe, wherein the cycling cleat is configured to engage a pedal on a bicycle; and screws engaging the screw holes to hold the cycling cleat in place against the bottom surface of the sole.

36. The cycling shoe of claim 16, further comprising: a cycling cleat coupled to a bottom, outer surface of the sole of the cycling shoe, wherein the cycling cleat is configured to engage a pedal on a bicycle; and screws engaging the screw holes to hold the cycling cleat in place against the bottom surface of the sole.

37. The cycling shoe of claim 22, further comprising:
a cycling cleat coupled to a bottom, outer surface of the
sole of the cycling shoe, wherein the cycling cleat is
configured to engage a pedal on a bicycle; and
screws engaging the screw holes to hold the cycling cleat 5
in place against the bottom surface of the sole.
38. The cycling shoe of claim 27, further comprising:
a cycling cleat coupled to a bottom, outer surface of the
sole of the cycling shoe, wherein the cycling cleat is
configured to engage a pedal on a bicycle; and 10
screws engaging the screw holes to hold the cycling cleat
in place against the bottom surface of the sole.
39. The cycling shoe of claim 28, further comprising:
a cycling cleat coupled to a bottom, outer surface of the
sole of the cycling shoe, wherein the cycling cleat is 15
configured to engage a pedal on a bicycle; and
screws engaging the screw holes to hold the cycling cleat
in place against the bottom surface of the sole.
